DANIEL ZIERER, OF GUEBWILLER, FRANCE, ASSIGNOR TO NOUVELLE SOCIETE DE CONSTRUCTION CI-DEVANT N. SCHLUMBERGER & CIE., OF GUEBWILLER, HAUT-RHINE, FRANCE.

FRAME FOR COMBING MACHINES.

Application filed May 12, 1923. Serial No. 638,444.

To all whom it may concern:

Be it known that I, DANIEL ZIERER, a citizen of the Republic of France, residing at Guebwiller, Department of Haut-Rhine, 5 and Republic of France, have invented certain new and useful Improvements in Frames for Combing Machines, of which the following is a full, clear, and exact description.

This invention relates to combing machines of the Heilmann type and other types based on the same principle according to which the lap whilst being held by a straight nipper is combed by the passage of rows of needles of a circular comb.

15 It is known that in this kind of combing machine as constructed hitherto, the upper devices such as amongst others the inlet, the feed apparatus, and the nipper, are mounted on the upper portion of a frame, the 20 lower portion of which comprises, amongst other parts, the cam shaft, the circular comb, the revolving brush and the doffer.

It is likewise known that, as regards the circular comb which is composed of one, 25 two or more comb segments, the renewal of damaged rows of needles is attended by great drawbacks for the following reasons:—

When the comb segment or segments are situated in a favourable position for being removed from the top, the nipper is still closed and is therefore at its minimum distance from the comb segment; this is an unfavourable position and hinders the removal of the comb segments from the top.

35 It is therefore necessary to remove the comb segments from the back by running the machine backwards after having first removed the screws that fix them on the comb stock discs or spiders, and also certain 40 other parts which would prevent the removing operation. This removing operation is therefore a very delicate procedure necessitating skillful and experienced handiwork whilst at the same time entailing great loss 45 of time. These drawbacks are repeated when placing new segments into position, owing to the fact that it is desirable not to damage the new rows of needles especially as they have the finest pitch.

50 In order to remedy these drawbacks in part, so as to be able to remove and replace with the least difficulty the segment for re-

placing the needle bars, especially those having closely spaced needles, it has already been proposed to make the segment in two 55 portions. That expedient is however not perfect, because two comb segments fixed one behind the other on the comb stock, never revolve in the same perfectly circular manner as a single segment, so that this 60 constitutes a further drawback in the working of the combing machine.

The present invention has now for its object to obviate the aforesaid drawbacks, and for this purpose it consists in improvements in the frames of combing machines of the Heilmann type and machines based on this type, whereby the comb segments are rendered more accessible and can be removed from the top without difficulty, without requiring delicate handiwork, without throwing the machine out of adjustment and without loss of time; the replacing of the new comb segments into position being attended by the same advantages, in addition 75 to the important advantage of being able to use over again the comb segments made in one piece which has been hitherto impossible in the majority of modern combing machines.

80 These improvements forming the subject matter of the present invention consist in principle in making the frame of the combing machines in two portions, namely a portion on which are mounted amongst other devices, the inlet, the feed apparatus and the nipper; this portion constitutes the upper frame portion and is adapted to rock on a pivot pin fixed to the other portion, namely the lower frame portion which comprises amongst other devices a circular comb, in such a manner as to enable the circular comb to be withdrawn, by moving back the devices carried by the upper frame portion, and thus allowing of removing and replacing 85 the comb segments easily and rapidly and without throwing the machine out of adjustment.

90 In order to enable this invention to be more fully understood, a constructional 100 form thereof is hereinafter described and illustrated by way of example in the accompanying drawings in which:—

Figure 1 is a side elevation of a Heilmann

combing machine, the frame being shown closed, and the machine being in working position, and

5 Figure 2 is a similar view showing the frame opened to allow of replacing the comb segments.

From these figures it will be perceived that the improved frame is composed of two portions 1 and 2, the upper frame portion 10 2 being adapted to be turned backwards by rocking on the pivot pin 3 fixed on the lower frame portion 1, the extent of this backward movement being such that it allows the circular comb 4 to be completely 15 disengaged from the nipper 5.

The upper portion 2 of the frame which latter is repeated correspondingly on the other side of the combing machine, constitutes with its two cross pieces 6 and 7, a 20 rigid framework carrying, amongst other devices, the inlet, the feed apparatus and the nipper. A rigid fastening together of the two parts 1 and 2 is assured by any suitable fastening device, such as for instance, 25 bolts 8 and nuts 9, the undoing of which allows the upper frame portion 2 to be rocked until a heel piece or stop 10 comes against a shoulder 11 formed on or fixed to the lower frame portion 1.

30 In this position, shown in Figure 2 the comb segments can be removed from the top and be replaced quickly and without difficulty, and without disturbing the adjustment of the machine, owing to the fact that 35 the lower cross piece 7, which carries the nipper springs and the springs of the feed apparatus, rocks with the whole combination around the pivot pin 3.

When this operation is completed, the 40 movable frame portion 2 is brought back into its original position and fastened to the frame portion 1 by means of the bolts 8 and nuts 9, or in any other manner.

It is to be understood that for the purpose of realizing the improvements forming the subject matter of the present invention and applying them to the various types of 45 combing machine based on the Heilmann principle, the said improvements may undergo modifications, alterations in details, 50 and also that suitable mechanical equivalent may be used, without thereby departing from the nature of this invention.

What I claim is:

1. In a combing machine of the Heilmann type having an inlet, feed apparatus, a nipper and a circular comb formed in segments, a fixed frame on which the circular comb is journalled, a movable upper frame to carry the inlet, the feed apparatus and the nipper, and a pivotal connection between the fixed frame and the upper frame to enable the latter to be swung to withdraw the nipper from the comb to permit easy and rapid replacement of the comb segments 65 without throwing the machine out of adjustment.

2. In a combing machine of the Heilmann type having an inlet, feed apparatus, a nipper and a circular comb formed in segments, 70 a fixed frame on which the circular comb is journalled, a movable upper frame to carry the inlet, the feed apparatus and the nipper, a pivotal connection between the fixed frame and the upper frame to enable the latter to be swung to withdraw the nipper from the comb to permit easy and rapid replacement of the comb segments without throwing the machine out of adjustment, 75 and means for securing the movable frame 80 firmly to the fixed frame when the machine is to be operated.

In witness whereof, I hereunto subscribe my signature.

DANIEL ZIERER.
